Inventor:
F. J. Pew.
by F. J. Pew. Attest.

UNITED STATES PATENT OFFICE.

FRANKLIN JONES PEW, OF ST. CATHARINES, ONTARIO, CANADA.

AUTOMOBILE BODY.

Application filed October 20, 1924, Serial No. 744,829. Renewed August 8, 1925.

To all whom it may concern:

Be it known that I, FRANKLIN JONES PEW, a subject of the King of Great Britain, and a resident of the city of St. Catharines, in the county of Lincoln, in the Province of Ontario, Canada, have invented certain new and useful Improvements in Automobile Bodies, of which the following is the specification.

10 My invention relates to improvements in automobile bodies and the object of the invention is to devise means whereby the backs of the front and rear seats may be turned down to constitute berths or beds.

15 A further object is to provide means whereby the seat portion can be readily pushed forwardly as the back of the seat is turned down into alignment therewith.

20 A still further object is to devise means whereby the top of the cushion of the seat portion when pushed forwardly will assume a substantially horizontal position instead of being inclined downwardly from front to rear, as is the case when the seat portion is 25 in the normal position.

Another object is to devise means for rigidly supporting the back of each seat portion on the floor of the vehicle when in its normal position.

30 My invention consists of a device constructed and arranged all as hereinafter more particularly described and illustrated in the accompanying drawing in which:

Fig. 1 represents a vertical longitudinal section through a closed automobile body provided with seats constructed according to my invention.

35 Fig. 2 is an enlarged perspective view of the frame construction attached to the seat and back portions of a seat, and also showing the block base upon which the frame is mounted.

Like characters of reference indicate corresponding parts in the different views.

40 1 is the floor of the car. 2 are block shaped bases for each seat, each of said bases having the upper surface thereof inclined downwardly from an intermediate point to its forward end and the rear portion of such upper surface substantially horizontal.

Four independent bases 2 are used, suitably positioned on the floor of the car and either built up to their required form or constructed solid. These bases are rigidly secured to the floor of the car and the front and rear bases of each pair are suitably spaced apart. 55

3 are the seat portions adapted to be applied to the bases 2, said seat portions having a lower surface corresponding in shape to the upper surface of the supporting bases. 4 is a U-shaped frame of strip material secured to the side and front lower edges of the seat portions 3, and the forward portions of its side members inclined downwardly from rear to front to correspond with the inclination of the lower surface of the seat 3 and the coacting face of the base 2. The lower edge of the U-shaped frame 4 is 70 positioned below the lower surface of the seat 3 and thus when the seat is applied to the base the frame 4 holds it against lateral or longitudinal displacement. 65

5 are upwardly extending brackets formed 75 at the rear end of the members 4 to which are pivotally secured the brackets 6 of the supporting members 7 which are secured to the side faces of the seat backs 8, the brackets 6 being positioned intermediately of the 80 length of such members 7. The lower ends of the members 7 depend below the lower edges of the seat backs and are stepped into the sockets 9 countersunk into the floor 1 of the car. 85

10 is a laterally extending roller journaled at its ends in the frame 4 in the vicinity of the rear end thereof. 11 is a brace rod extending between the brackets 5.

In Figure 1 of the drawing the near seats 90 are illustrated in the normal position and the far seats are illustrated swung into the berth or bed form. In order to move the seats from their normal position into the bed form the lower ends of the members 7 95 are unstepped from the sockets 9 and the seat portions 3 lifted a slight extent so as to permit the rollers 10 to ride on the horizontal portions of the base 2. The back portions 8 are now swung down rearwardly 100 and the seats pushed forwardly until they assume the position illustrated by the far

ther seats in Figure 1, wherein the forward edge of the seat portion rests on the floor in front of the base 1, thus the upper surface of the seat portions will lie substantially horizontal instead of being inclined downwardly from front to rear, as in the normal position the upper surfaces of the seat backs are in alignment with the upper surfaces of the seats.

10 The upper edge of the forward seat backs is set at an angle to the front surfaces thereof so that when it is turned downwardly into the bed position it will lie parallel to the forward edge of the rear seat portions. The 15 back portions of the rear seats are similarly swung down as indicated in the case of the farther seats in Figure 1 and when this is done a bed of full length will be constituted.

15 In making up the beds the preferable way would be to swing one set of seats out of the way by unstepping the forward ends of the members 7 and swinging the seat backs onto the seats and by grasping such free ends of the members 7 move the seats 25 out of the way so that the remaining seats can be made up into a bed with the minimum of trouble. This will facilitate applying the bed clothes. The remaining seats are now made up into the form of a bed 30 and the bed clothes applied thereto.

Thus, when the seats are moved into the bed position two independent berths or beds will be constituted in the body of the car.

35 To move the seats into their normal seating position it is only necessary to pull up the seat backs and pull rearwardly on the seat portion when the free ends of the members 7 may again be stepped into the sockets 9.

40 From the above description it will be apparent that I have devised a simple and effective seating arrangement in which the seats can be readily moved into position whereby they assume the form of berths or beds, and, moreover, I have devised detachable means for supporting the seat backs which will make such backs rigid when in the seating position.

50 The rollers 10 when the seat portions 3 are in the normal seating position on the bases 2 will be positioned so as to lie slightly below the rear upper edge of the bases 2 and thus prevent forward displacement of such seat portions from the bases unless such seat portions are raised a small extent at their rear ends.

55 What I claim as my invention is:

1. In an automobile body, a seat base having an upper surface with a substantially horizontal rear portion and a forward portion inclined upwardly from its forward edge to the junction with the rear portion, a seat having a substantially horizontal rear portion and an inclined front

portion on its lower surface, the inclination of the forward portion of the lower portion of the seat corresponding with the inclination of the forward portion of the upper surface of the base, a back portion hinged to the seat portion, and means for supporting the back portion in its normal position.

2. In an automobile body, a seat base having an upper surface with a substantially horizontal rear portion and a forward portion inclined upwardly from its forward edge to the junction with the rear portion, a seat having a substantially horizontal rear portion and an inclined front portion on its lower surface, the inclination of the forward portion of the lower portion of the seat corresponding with the inclination of the forward portion of the upper surface of the base, a back portion hinged to the seat portion, means for supporting the back portion in its normal position, a U-shaped frame secured to the seat portion, the ends of the legs of the U-shaped frame directed rearwardly, depending members secured to the sides of the back portion and hinged to the legs of the U-shaped frame, and means for detachably supporting the lower ends of the depending members on the floor of the body.

3. In an automobile body, a seat base having an upper surface with a substantially horizontal rear portion and a forward portion inclined upwardly from its forward edge to the junction with the rear portion, a seat having a substantially horizontal rear portion and an inclined front portion on its lower surface, the inclination of the forward portion of the lower portion of the seat corresponding with the inclination of the forward portion of the upper surface of the base, a back portion hinged to the seat portion, means for supporting the back portion in its normal position, a U-shaped frame secured to the seat portion, the ends of the legs of the U-shaped frame directed rearwardly, depending members secured to the sides of the back portion and hinged to the legs of the U-shaped frame, and sockets in the floor of the body, the lower ends of the depending members stepped into the sockets.

4. In an automobile body, a seat base having an upper surface with a substantially horizontal rear portion and a forward portion inclined upwardly from its forward edge to the junction with the rear portion, a seat having a substantially horizontal rear portion and an inclined front portion on its lower surface, the inclination of the forward portion of the lower portion of the seat corresponding with the inclination of the forward portion of the upper surface of the base, a back portion hinged

to the seat portion, means for supporting the back portion in its normal position, a U-shaped frame secured to the seat portion, the ends of the legs of the U-shaped frame directed rearwardly, depending members secured to the sides of the back portion and hinged to the legs of the U-shaped frame,

a transverse roller journalled at its ends in the legs of the U-shaped frame in the vicinity of the extremities of the legs, and means for detachably supporting the lower ends of the depending members on the floor of the body. 10

FRANKLIN JONES PEW.
